(57) **CLAIM**

The ornamental design for a chromatography column assembly end cap, as shown and described.

DESCRIPTION

FIG. 1 is a perspective view of the end cap;

FIG. 2 is a side view of end cap;

FIG. 3 is a side view of the end cap;

FIG. 4 is a side view of the end cap;

FIG. 5 is a side view of the end cap;

FIG. 6 is a face view of the end cap; and,

FIG. 7 is an opposite face view of the end cap.
